UNITED STATES PATENT OFFICE.

FREDERICK M. SAYRE, OF MICHIGAN CITY, INDIANA.

SECTIONAL METAL SIGNBOARD.

Application filed March 2, 1923. Serial No. 622,286.

To all whom it may concern:

Be it known that I, FREDERICK M. SAYRE, a citizen of the United States, residing at Michigan City, in the county of LaPorte 5 and State of Indiana, have invented a certain new and useful Improvement in Sectional Metal Signboards, of which the following is a specification.

My invention relates to sectional metal 10 signboards and the general object of the invention is to provide a simple sectional board composed in the main of identical panels adapted to interfit with each other and provided with means for holding them 15 assembled to maintain them as a single, unitary structure. Contributory to this general object it is my purpose to provide special expedients by which the signboard will lend itself to quantity production and render available approved shop methods. Another object of the invention is to provide 20 a construction such that the amount of work necessary at the point of erection will be reduced to a minimum—chiefly that of bringing the panels into interfitting 25 relation at the edges and mounting the panels in a bordering frame. Still another object is to provide a construction which will produce a sign of great rigidity thereby enabling it to successfully withstand high wind 30 pressure and stresses and strains due to other causes. Still another object is to provide a sectional sign in which the connection between panels will be airtight thus 35 avoiding the danger of having posters blown from the surface of the sign in spots in cases where posters are applied to the front of the sign. It is well known by bill 40 posters and others that where signs of ordinary construction are employed cracks frequently open up which permit the wind to blow against the back of the exposed portion of the poster, thus often causing a portion of the poster to be torn from its place.

As a result of my invention the sign is 45 windtight and there is no possibility of the paper being blown off.

I accomplish my objects by the construction shown in the accompanying drawings 50 in which—

Figure 1 is a front view of a completed sign, portions of the frame being broken away to reveal the internal construction.

Figure 2 is a rear elevation in which certain parts are similarly broken away to 55 show the construction beyond.

Figure 3 is a sectional view on the line 3—3, Figure 1.

Figure 4 is a plan section on the line 4—4, Figure 1.

Figure 5 is an enlarged top view of individual panels showing the manner in which they interfit at the ends.

Figure 6 is a sectional view enlarged to a still greater scale showing the interfitting construction at the edges of the panel.

Figure 7 is a perspective view showing the back of a panel.

Figure 8 is a sectional detail showing a modified form of frame work.

Like numerals denote like parts throughout the several views.

As previously indicated, the structure is of the sectional type and composed in general of panels which interfit at the edges 75 and a framework which holds them in assembled relation. In the drawings I have illustrated a form of panel which has many advantages not only as embodying the general principle of the invention, but, in addition, promoting quantity production and harmonizing with good shop practice. An individual panel is shown separately in perspective in Figure 7. These panels in practice are usually composed of galvanized 80 sheets, and for ordinary uses it is common to select a stock size of 30 x 120 inches. It will be understood from this that for the larger sizes of signboards the individual 85 sheets are of considerable size and consequently are subjected to considerable wind pressure when in use. It will be understood, however, that sheets of various sizes 90 may be employed within the spirit of the invention.

According to the design shown, one edge of the sheet has a "box break," that is, is folded back upon itself so as to form a rectangular box section 2 with an additional flange or foot 3 which is secured to the back 95 of the sheet. By preference this flange 3 is spot welded to the sheet as shown at 4, Figure 6, but it will be obvious that riveting or other forms of attachment might be substituted. Spot welding is preferable, however, as it does not require a puncturing of the metal, and no fastening devices are visible. The sheet is "notched out" or cut away at the corners 6 so that the box section will terminate short of the ends of the 100 sheet to permit the bordering frame to overlap the sheet as will be hereinafter ex-

plained. While it is possible to substitute some other form of section at the edge of the panel, the design illustrated is excellent for the reason that the metal is integral and also that a rectangular box section affords great stiffening to the panel and also affords an advantageous shape for co-operating with the channeled edge of the adjacent panel. It also assists in producing a wind tight connection at the joints of the board.

Except for the finishing panel the panels are all alike and each one has at the edge opposite to the one with the box section a channel bar 8 having a marginal flange or foot 10 by which it is secured to the back of the sheet. By preference this is spot welded as shown at 12, Figure 6, although other fastening means may be substituted, as previously explained. It terminates short of the ends of the panel to permit the bordering frame to overlap the ends of the panels. Said channel 8 is rectangular and of such dimensions that the box section 2 will fit fairly snugly into it to prevent rattling or play after the sign has been erected. It will be evident that when the edges of the panels are interfitted as illustrated, for example, in Figures 4 and 8, the panels will be braced not only by the element which is fastened to them but they will cooperate with each other to brace each other. The result is that even though the panels are 10 feet high they will, when erected, possess great stiffness and will be able easily to resist almost any degree of wind pressure that can occur. Another result of the construction is that the board is impervious to wind and weather. In many bill posters, signboards, cracks may be found which will let moisture thru from the back and also admit wind pressure. The moisture softens the paper and the paste and the result is, quite commonly, that sections of the poster in front of and near such cracks will be torn off and the poster ruined. This is impossible with my construction.

While not essential, it is desirable that the panels at both extremities of the sign board shall present a box section as this contour is better for attachment to the bordering frame. I accomplish this by making a "finishing" or terminal panel shown at the right end of Figure 4. It is in all respects like the others except that its channel 14 is slightly lower than the others and thus is able to fit thereinto. In assembling, the terminal panel is reversed from the others, end for end, and thus there is a box section at both ends of the group.

The panels are held in fixed relation by a marginal frame which may be somewhat varied in design. An advantageous form is shown in section in Figures 3 and 4. In this design the frame consists of a front

molding 16, a back strip 17 and a marginal strip 18. These are nailed or otherwise secured together. In the case of nailing, nails 19 pass through the molding and through the panel into the back strip 17. The marginal strip 18 lies at right angles to the plane of the parts 16 and 17 and not only forms a finishing strip but also a cornice for protecting the frame (and the sign to a considerable extent) from the weather.

In Figures 1 to 4 I have shown the frame as being made of wood. In many cases I prefer to employ sheet metal and have illustrated a good design in Figure 8 in which the frame has a cornice-like hollow section 20 having a vertical bottom flange 21 and a horizontal top flange 22. In erecting the structure nails 24 are driven through the bottom flange and upper end of the panel into a back strip 26, although other fastening means may be substituted. In the same way it is common to apply nails 27 to the top flange 22 and drive them through the flange into the top of strip 26. This produces a sign of attractive appearance and one that is practically all metal.

In practice the individual panels and the members composing the frame are shipped unassembled. When the place of erection is reached all that is necessary is to bring the panels together end to end, fitting the box sections at one end of a panel into the channel at the adjacent edge of the adjacent panel. The frame members are then applied and their effect is to permanently hold the panels assembled, preventing the panels from separating laterally and also preventing them from shifting longitudinally. Consequently when the parts have been assembled the structure becomes not only unitary but extremely rigid and capable of withstanding great stresses and wind pressure. It is also moisture proof and wind proof with the resulting advantages hereinabove mentioned.

It will be understood that various means may be employed for holding the signboard upright, for example, posts 28 driven into the ground as indicated in Figures 1 to 4. The manner of supporting the sign, however, forms no particular part of my invention.

Having thus described my invention what I claim as new and desire to secure by Letters Patent is:

1. A sectional sign board having sheet metal panels having interlocking longitudinal edges whereby relative longitudinal movement might occur but transverse movement, perpendicular to the plane of the panels, is prevented, one edge of a panel being channeled and the other edge having a bent portion for stiffening the panel and making a sliding fit with the channel on the adjacent panel, independent border

strips at the ends of the panels extending across a plurality of them for preventing relative longitudinal movement, and means for preventing the panels from moving apart in the direction of their planes.

2. A sectional sign board comprising sheet metal panels arranged edgewise in the same plane, one edge of a panel having a channel running lengthwise of the panel 10 and the other edge of the same panel having a box section fitting into a similar channel on the next panel, the box section being formed by bending the metal back upon itself and securing it to the back of the 15 sheet, means for holding the box section in the adjacent channel and means for preventing relative longitudinal movement of the panels.

3. A signboard having a plurality of 20 identical metallic panels having a channel at one edge and a box section at the opposite edge whereby when two panels are as-

sembled edge to edge the box section of one panel will fit into the channel of the adjacent panel, and a frame adapted to fit 25 over the ends of the panels for holding them against endwise movement, the box sections and channels terminating short of the ends of the panels to clear the frame.

4. A signboard having a plurality of 30 identical metallic panels having a channel at one edge and a box section at the opposite edge whereby when two panels are assembled edge to edge the box section of one panel will fit into the channel of the 35 adjacent panel, means for preventing the panels from moving away from each other in a direction transverse to the interfitting edges, and means for preventing the panels from moving relatively to each other in a 40 direction parallel to their interfitting edges.

In witness whereof, I have hereunto subscribed my name.

FREDERICK M. SAYRE.
